(57) **CLAIM**

The ornamental design for a work station, as shown and described.

DESCRIPTION

FIG. 1 is an oblique view of the work station illustrating rotatable extensions at each end of a central work surface;

FIG. 2 is a front view of the invention shown in FIG. 1;

FIG. 3 is a back elevation view of the invention shown in FIG. 1;

FIG. 4 is a side elevation view of the invention shown in FIG. 1;

FIG. 5 is an opposite side view of the invention shown in FIG. 1; and

FIG. 6 is a plan view of the invention shown in FIG. 1;

FIG. 7 is a bottom view of the invention shown in FIG. 1;

FIG. 8 is a bottom view of the invention shown in FIG. 1 with one of the wings moved to a second position; and,

FIG. 9 is a bottom view of the invention shown in FIG. 1 with an opposite one of the wings moved to a second position.
